UNITED STATES PATENT OFFICE.

CHRISTOPHER W. BROWN AND WILLIAM ASA BROWN, OF MASS., MICHIGAN.

ROTARY ENGINE.

1,221,326.

Specification of Letters Patent. Presented June 26, 1917.

Application filed October 14, 1915. Serial No. 55,325.

To all whom it may concern:

Be it known that we, CHRISTOPHER W. BROWN and WILLIAM A. BROWN, citizens of the United States, and residents of Mass., in the county of Ontonagon and State of Michigan, have invented a new and Improved Rotary Engine, of which the following is a full, clear, and exact description.

10 Our invention may be embodied in a rotary combustion engine, or in a steam or other fluid-driven engine, or in a rotary pump, it being understood that the term engine includes a pump.

15 Our improved engine is characterized by a rotor having movable vanes or pistons and by a stator having an annular working cylinder in which the vanes operate and which is divided at the center by the rotor into two side chambers. The vanes are arranged to shift transversely to project laterally beyond either side of the rotor into either side of the cylinder. The side walls of the cylinder presented to the opposite 20 side edges of the vanes are undulated in a manner hereinafter described to shift the vanes transversely of the rotor and to constitute cut-offs and abutments against which the force of the gas or fluid is received simultaneously with the exertion of the force on the vanes to actuate the rotor, the arrangement constituting essentially, a valveless engine having a distinctive cycle of 25 operations, the illustrated example being equivalent to a four-cylinder engine, by reason of the particular number of undulations in the cylinder.

30 The invention will be particularly explained in the specific description following.

Reference is to be had to the accompanying drawings forming a part of this specification in which similar reference characters indicate corresponding parts in all the 35 views.

Figure 1 is a side view of an internal combustion engine embodying our invention;

Fig. 2 is an edge view thereof;

Fig. 3 is a section on the line 3—3, Fig. 1;

50 Fig. 4 is a section on the line 4—4, Fig. 1;

Fig. 5 is a transverse section through the rotor and the opposite sides of a casing or a stator showing the said parts separated before assembling;

55 Fig. 6 is a fragmentary face view of the rotor;

Fig. 7 is a transverse section through the rotor on the line 7—7, Fig. 6;

Fig. 8 is a face view of the rotor when embodying our invention in a steam or so other fluid-driven engine rather than an internal combustion engine;

Fig. 9 is a view similar to Fig. 6, but showing the parts as constructed when employing the rotor of the construction shown in Fig. 8; and

Fig. 10 is a view similar to Fig. 4, but illustrating the invention embodied in an engine other than an internal combustion engine.

Referring at first more particularly to Figs. 1 to 7, the stator provides a casing 10, divided at the median line, provided with suitable base members 11; the side members of the casing are fastened by any suitable means such as ears 12, and bolts 13. The construction illustrates an internal combustion engine and therefore has the casing variously formed with a water jacket 14, the inlets and outlets of which are indicated at 14^a and 14^b.

The casing provides at the interior, adjacent to the periphery, an annular chamber 15, constituting the working cylinder of the engine. A shaft 16, is journaled in the hub 17, of the casing, and rigid theron is a rotor 18. The rotor 18, is formed with annular dépressions 19, at opposite sides.

The rotor 18, carries vanes or pistons, operative in the cylinder 15. There are two 90 vanes 180 degrees distant from each other and they are identical in all respects in construction and arrangement, the only difference being that certain ports are provided in the rotor adjacent to one of the 95 vanes while no ports are provided at the diametrically opposite vane. We have designated generally by the numeral 20, the vane at the ports and the opposite vane by the numeral 20^a. As both vanes are identical in construction, their details will be identified by their corresponding reference numbers.

Thus, each vane is slideable transversely in an opening 25 of the rotor so as to have movement from side to side of the 105 rotor. Each vane includes spaced sides in connection with which suitable elements are provided to effect a fluid-tight engagement between the vanes and the rotor and between the vanes and the side walls of the 110 cylinder; for the purpose T-shaped side elements 21 are shown, the shanks of which

are received between the members of the vanes 20, and 20^a, and are pressed outwardly against the opposite side walls of the cylinder 15, by an expansion spring 22. Similarly against the sides of the said vanes, between the same and the walls of the opening 25, strips 23, are employed, against the backs of which springs 24 act to force the strips against the vanes. The numeral 26, indicates guide ribs in the opening 25, against which the vanes 20, 20^a, bear at opposite sides.

The opposite side walls 27, of the cylinder 15, are undulated, the number of undulations being governed by the number of vanes 20, 20^a, and hence, the arrangement illustrated is adapted to coact with vanes on the rotor 180 degrees apart. The arrangement presents at two points, on each wall of the cylinder, convexed surfaces against which the sides of the rotor 18 will contact, that is to say, on each side of the rotor there are two points at an angle of 180 degrees which come in contact with the rotor, and these 25 points on the respective sides are quadrantally making four points in all at an angle of 90 degrees, and alternately at opposite sides of the rotor, with which points the cylinder comes in contact with the said 30 rotor. The undulations of the walls 27, are such that every point on one wall is equidistant from a point directly opposite it at the opposite side of the rotor so that at all points around the cylinder, the distance 35 between the walls thereof corresponds with the width of the vanes. Also, the surface of each wall 27, at any given point is perpendicular to the center of the shaft 16, so as to present a surface parallel with the 40 side edge of a vane regardless of the angle of the vanes to a horizontal line drawn through the center of the shaft 16.

We have indicated pipes 28, 29, at opposite sides of the engine, the one of which 45 will constitute an inlet for fuel and the other an exhaust, according to the direction of rotation. At present it may be considered that 28 represents a supply pipe. The pipes 28, 29, communicate with transverse openings in the casing, the inlet opening being indicated by the numeral 30, in Figs. 3 and 5, and at opposite sides of the rotor 18, annular channels 31, 32, are formed communicating with said openings. Thus, there is 50 non-interrupted communication between the supply pipe 28, and the annular channel 31, in the rotor, and similarly a non-interrupted communication between the annular channel 32, at the opposite side and the pipe 29. Between the annular depressions 19, in the rotor 18, and the annular depressions 31, 32, there will thus be produced annular ribs or 55 walls 33, at each side of the rotor. Radial ports 34, 35, are formed one in each rib 33, establishing communication between the

channels 31 and 32, and the depressions 19. The said ports 34, 35, are at opposite sides of the vane 20, that is, one in front and one in the rear of the vane, one port in each rib 33. There are no ports adjacent to the vane 20^a, in the form of engine shown in Figs. 1 to 7. The positions of the ports 34, 35, are such that the vane 20 will have movement transversely of the rotor in a plane between the said ports. An oblique port 36, extends 70 from the channel 31, at the port 35, at one side of the rotor to the depression 19 at the opposite side of the rotor. Also, an oblique port 37, extends from the opposite channel 32, and port 34 to the depression 19, at the 80 opposite side of the rotor. In Fig. 7, the arrow α indicates the direction of the fuel inlet to the port 34, (by way of the channel 31), and the arrow α' at the left indicates the direction of exhaust from the port 35, to 85 the exhaust pipe 29, (through the channel 32).

The piston 20 serves to draw in a charge in the rear thereof while it scavenges at its forward side. The trailing piston 20^a at 90 its forward side compresses the charge previously drawn in by piston 20, while the force of an explosion acts against the back of the piston 20^a, the compressed charge having been transferred from the front to the 95 back of the piston 20^a by means hereinafter described.

Spark plugs 41, are provided on the engine corresponding with the points at which the undulating walls 27 of the cylinder 15, 100 are touched by the sides of the rotor 18. Each spark plug is fitted in a tube 42, and in fixed relation with said tube and in communication therewith, is a rotary trunk valve 43. A by-pass 44, is formed in the 105 casing communicating at both ends with the cylinder 15, at opposite sides of each point in the cylinder touched by the rotor 18. Said by-pass is commanded by the trunk valve 43, which has at one side, an opening 110 45. Turning movement is given to the trunk valve at the same speed as the rotor 18, the means illustrated for this purpose comprising a pinion 46, on each tube 42, arranged to be driven from a pinion 47, on 115 the power shaft 16, there being in the present example, intermediate gear wheels 48, to give the proper speed of revolution to the rotary valves.

The valves 43, thus coact with the vanes 120 20, and 20^a, and the ports 34, 35, 36, 37, to effect the cycle of operations. Thus, the vane 20, having passed a point of contact with the wall 27, at one side of the cylinder 15, it will begin to draw in a supply of fuel 125 behind said vane through port 34. The fuel thus drawn in by the vane 20, will be compressed by the trailing vane 20^a, the gases being forced into one end of the by-pass 44, and into the trunk valve 43, and the tube 42, 130

having the spark plug 41. The rotation of the valve 43 is timed so that when the vane 20^a, has passed beyond the opposite end of the by-pass, the valve will be turned sufficiently to close the entrance end of the by-pass and establish communication between the opposite outlet end and the valve opening 45, at which time the spark will occur and cause the explosion in the rear of the 10 vane 20^a, and the cycle will be continued. The scavenging by the forward side of the advance vane 20, in the right-hand chamber will be through ports 36, 35, (to channel 32, and exhaust 29).

15 Any suitable housings 50, may be provided for the gearing; also, there may be casing elements 51, at the spark plugs, having chambers 14^a, in communication with and forming part of the water jacket 14.

20 Referring now, to Figs. 8, 9 and 10, which illustrate an engine to be driven by steam or other fluid without an explosion, the construction is essentially the same as the first described engine, with this difference, that 25 the same ports are provided in the rotor adjacent to the trailing vane 20^a, that are provided adjacent to the advance vane 20, and these ports are identical with the ports in the internal combustion engine. The cas- 30 ing elements 10^a, with the steam or compressed air engine, require no water jacket. They provide a cylinder or annular working chamber 15^a, corresponding in all re- 35 spects with the cylinder 15, and in the rotor 18^a, annular depressions 19^a, corresponding with the depressions 19, are provided at the cylinder 15^a. The side walls 27^a, of the cylinder 15^a, are undulated exactly as in the first described construction.

40 Inasmuch as the vanes 20 and 20^a are the same in the form of engine shown in Figs. 8 to 10, as in the other, we have employed the same reference characters applied to the corresponding parts so that these need not 45 be further referred to. The ports 34^a, 35^a, correspond with the ports 34, 35, as do also, the ports 36^a, 37^a, correspond with the ports 36, 37. The same arrangement of ports is 50 provided at the vane 20^a, the radial ports being indicated by the characters 34^b, 35^b, and the oblique ports by the characters 36^b, 37^b.

55 In operation the steam or compressed air is received in the channel 31^a, assuming the engine is rotating in the stated direction of the internal combustion engine. The trunk valves and by-pass of the internal combustion engine are omitted. The steam will pass through the radial ports 34^a, 37^a, 34^b, 37^b, in the annular rib 38^a, to the respective 60 right and left chambers of the cylinder 15^a, and at the back of the vanes 20, 20^a, as the latter pass the high points of the undulated walls 27^a, and by exerting pressure at the back of the vanes, will drive the rotor, the 65 steam exhausting through the ports 35^a, 36^a,

35^b, 36^b, in the same manner as in the internal combustion engine.

Having thus described our invention, we claim as new and desire to secure by Letters Patent:

1. A rotary engine including an annular cylinder, a rotor operating in the cylinder, and having an annular depression in each side face thereof opposite the side walls of the annular cylinder and movable transversely disposed vanes carried by the rotor and extending across the said annular depressions to the walls of the cylinder, there being means at intervals in the cylinder to move the vanes and coat therewith to subdivide the cylinder at separated points around same, and the rotor having ports communicating with the said annular depression and thus with said cylinder for the inlet and discharge of a fluid in front of and behind a vane. 70

2. A rotary engine including an annular cylinder, a rotor operating in the cylinder and having an annular depression in each side face thereof opposite the side walls of the annular cylinder and vanes carried by the rotor and extending across the said annular depressions to the walls of the cylinder, and movable transversely of the rotor, the cylinder having means to move the vanes 80 transversely at successive points around the cylinder and to coat with said vanes to subdivide the cylinder at separated points around the same, and the rotor having ports communicating with the said annular depression and thus with said cylinder for the inlet and discharge of a motive fluid, the ports being disposed adjacent to a vane and respectively behind and in front of the vane. 90

3. A rotary engine including an annular cylinder, having undulating side walls, a rotor operating in the cylinder and dividing the same into chambers, and having an annular depression in each side face thereof opposite the side walls of the annular cylinder and vanes carried by the rotor into said depressions and transversely movable across the rotor to project into either of the side chambers into which the rotor divides the 110 cylinder, the rotor contacting at its side surface alternately with the undulating walls at the opposite sides at intervals around the cylinder, there being ports in the rotor, communicating with both depressions of the rotor and thus with the chambers of the cylinder for the inlet and discharge of a motive fluid behind and in front of a vane. 115

4. A rotary engine including an annular 125 cylinder, a rotor operating in the cylinder and dividing the same into annular chambers disposed at opposite sides of the rotor, the said rotor having annular depressions at opposite sides and transversely disposed 130

- 4
- vanes on the rotor and movable transversely thereof to project into either side chamber of the cylinder, there being means in the cylinder to move the vanes transversely, said 5 means coacting with the vanes and with the side of the rotor to cut off each chamber at intervals, and subdivide the same at separated points around the cylinder, and the rotor having ports communicating with both 10 annular depressions and thus with the chambers of the cylinder for the inlet and discharge of a motive fluid in the rear of and in front of a vane.
5. A rotary engine including an annular cylinder having undulating side walls, a rotor operating in the cylinder and dividing the same into annular chambers disposed at opposite sides of the rotor, the said undulating walls contacting with the sides of the 15 rotor alternately at opposite sides of the rotor and serving to cut off each side chamber and subdivide the same at intervals around the cylinder, and vanes carried by the rotor and transversely movable to follow the undulating lines of the cylinder walls, the rotor having annular depressions opposite the cylinder walls, and ports communicating with said depressions and thus 20 with both side chambers of the cylinder for the inlet and discharge of a motive fluid behind and in front of a vane.
6. A rotary engine including an annular cylinder, having undulating side walls, a rotor operating in the cylinder and having 25 annular depressions at the cylinder, said rotor dividing the cylinder into annular side chambers, transversely disposed vanes carried by the rotor, the vanes being movable across the rotor to project into either 30 side chamber of the cylinder, there being annular channels in the rotor at opposite sides and separated from the annular depressions, and radial ports in the rotor establishing communication between the said annular depressions and annular channels at 35 the respective sides of the rotor, said ports being disposed one at each side of the rotor and at opposite sides of a vane, and there being an oblique port from each radial port 40 and the adjacent channel to the annular depression at the opposite side of the rotor.
7. A rotary engine including an annular cylinder, a rotor operating in the cylinder, vanes carried by the rotor and movable 45 transversely across the rotor, the rotor contacting at a side surface with the adjacent wall of the cylinder at intervals around the cylinder to cause a transverse movement of the vanes, there being ports in the rotor 50 communicating with the cylinder in front of and behind a vane and there being a bypass in the wall of the cylinder extending from one side of the point of contact of the

cylinder wall to the opposite side of said contact point, a rotary valve disposed in the bypass and having an opening therein, means for turning the valve in unison with the rotor to alternately connect its opening with the respective ends of the bypass, means to conduct an explosive charge to one of the 65 ports of the rotor, means to ignite the explosive charge at the said valve and bypass, and means to exhaust the products of combustion from the other of said ports.

8. A rotary internal combustion engine including a stator having an annular cylinder, a rotor disposed in the cylinder in a plane dividing the cylinder into separate side chambers, the walls of the chambers contacting at separated points with the respective sides of the rotor, a fuel inlet and outlet in said stator, ports in the rotor adjacent to each other and respectively communicating with the cylinder at opposite sides of the rotor, the ports being in communication respectively with the inlet and outlet of the stator, a combined suction and scavenging vane transversely movable on the rotor and extending across the same in a plane between said ports to contact with the opposite 80 side walls of the cylinder, a transversely movable trailing vane on the rotor acting to compress the charge drawn in by the first vane, and means to transfer the compressed charge to the back of the trailing vane and 85 explode the same.

9. A rotary internal combustion engine including a stator having an annular cylinder with undulating side walls, a rotor dividing the cylinder into annular side chambers, 100 transversely disposed vanes carried by the rotor and movable across the same by the undulations of the cylinder walls, the sides of the piston being in contact alternately at opposite sides with the undulations of the cylinder walls, and inlet and outlet ports in the rotor, said ports being disposed one at each side of the rotor and at opposite sides of a vane, so that the port at one side of the 105 rotor communicates with one side chamber in advance of the vane and the other port communicates with the other side chamber at the opposite side of the vane, there being lateral ports from each of said ports communicating with the opposite chamber and 110 there being ports leading respectively to and from the said inlet and outlet ports of the rotor through the stator.

In testimony whereof we have signed our names to this specification in the presence of 120 two subscribing witnesses.
